UNITED STATES PATENT OFFICE.

FREDERICK WIKOWSKY, OF COOKSVILLE, ILLINOIS.

METHOD OF TIGHTENING WIRES.

1,320,949.

Specification of Letters Patent.

Patented Nov. 4, 1919.

Application filed May 10, 1919. Serial No. 296,186.

To all whom it may concern:

Be it known that I, FREDERICK WIKOWSKY, a citizen of the United States, residing at Cooksville, in the county of McLean and State of Illinois, have invented certain new and useful Improvements in Methods of Tightening Wires, of which the following is a specification.

My invention relates to an improved method of tightening wires, and the object is to stretch the wire and to splice it and hold it in its tightened adjustment.

This invention embraces the steps by which the wire is stretched or spliced, as well as the means for accomplishing it.

In the accompanying drawings:—

Figure 1 is a view of a device for stretching the wire;

Fig. 2 is a view showing mechanism that may be used when the ends of the wire are broken;

Fig. 3 is an enlarged detail partly in section; Fig. 4 is a view showing broken ends of a barb wire after being repaired.

25 A, represents a frame, preferably U or V-shaped with an orifice 1 through the center, and having rollers at the ends, the rollers adapted to receive and bear upon the wire to be stretched, or the chain connecting the ends of the wire, as shown in Figs. 1 and 2.

The orifice receives a rod 3 having a hook 4 on one end adapted to receive the wire or chain, and the opposite end threaded to receive the T or L-shaped wrench 5, which is internally screw-threaded to turn upon the threads of the hook rod to draw the same through the frame and apply tension to the wire or chain.

35 The wire is indicated by the numeral 6, and the chain by 7, the chain being used only when the wire has become broken, and

is unnecessary when the wire is simply slack and needs tightening and is not broken.

The method consists in applying this tension until the wire is tight, either through 45 the wire directly as in Fig. 1, or through a chain connecting the ends of the broken wire, as in Fig. 2. In splicing, the splicing is done by a wire 9 made in two strands and bent around the wire to be stretched; if it 50 happens to be barbed, preferably back of the barbs to assist in holding the splice tight, and after it is thus fastened and while the main wire being stretched is under tension, a spike or rod is inserted between the 55 centers of the two strands of the splice wire and twisted until the same is tight, as shown in Fig. 3.

In this way by very simple means and method I am enabled to quickly stretch and 60 tighten the wire of a fence, and to fasten it securely in its tightened condition, whether this be at some point in the middle of a fence or at the broken ends.

An advantage of the splice is that after 65 the wire is once stretched in this way and tension applied, additional tension can be applied to the splice at any time by inserting a spike or tool and giving it a few added twists.

I claim:

The improved method of wire stretching which consists in applying a frame at two points to a wire or wires to be stretched and applying lateral strain between said points, 75 attaching a two-stranded wire or wires to the wire stretched at two points, and finally twisting these strands together to maintain the tension upon the wire or wires stretched.

In testimony whereof I affix my signature. 80

FREDERICK WIKOWSKY.
